UNITED STATES PATENT OFFICE.

WILLIAM WARREN DEAN, OF STAMFORD, CONNECTICUT, ASSIGNOR TO SPLITDORF ELECTRICAL COMPANY, OF NEWARK, NEW JERSEY, A CORPORATION OF NEW JERSEY.

IGNITION-GENERATOR.

1,389,034.

Specification of Letters Patent. Patented Aug. 30, 1921.

Application filed August 22, 1916. Serial No. 116,359.

To all whom it may concern:

Be it known that I, WILLIAM W. DEAN, a citizen of the United States, residing at Stamford, in the county of Fairfield and 5 State of Connecticut, have invented certain new and useful Improvements in Ignition-Generators, of which the following is a specification, reference being had to the accompanying drawing.

10 The invention relates broadly to generators used for ignition or the like and generally termed magnetos, and in detail to a magneto having a stationary current generating coil and a permanent magnet rotating between the pole pieces connected to the core of said coil.

An object of the invention is to provide a magneto of the above type with pole pieces which may be shifted relative to the fixed 20 pole pieces connected to the core of the coil for timing purposes.

A further object of the invention is to provide a magneto of the above type with means for short circuiting the poles of the 25 magnet which are not furnishing flux to the shiftable pole pieces.

These and other objects will in part be obvious and will in part be hereinafter more fully disclosed.

30 In the drawings which show by way of illustration, one embodiment of the invention:

Figure 1 is a vertical sectional view through a magneto having my improvements; and

Fig. 2 is a sectional view on the line 2—2 of Fig. 1.

The invention, as shown in the drawings, is embodied in a magneto for ignition purposes which consists of a permanent magnet 40 mounted on a suitable shaft adapted to rotate in suitable bearings. This magnet forms the rotor of the magneto. Associated with the rotor is a stationary current generating coil. Extending through the generating coil is a core having pole pieces connected thereto, which pole pieces are disposed relative to the permanent magnet so as to receive flux therefrom. This rotating 45 magnet is provided with a plurality of alternately N and S poles and the pole pieces are so disposed as to receive flux from adjacent poles of the magnet. These features 50 are broadly shown and described and

claimed in my co-pending application, Serial No. 108,498, filed July 10, 1916.

The present invention is directed more particularly to the pole pieces of the magneto and consists in providing auxiliary or shiftable pole pieces located between the 60 fixed pole pieces and the movable poles of the rotor.

The invention further consists in a shiftable short circuiting magnetic bar or piece which is so disposed as to short circuit the 65 poles of the rotor which are remote from the pole pieces.

Referring more in detail to the drawing:

I have shown the invention embodied in 70 a magneto having side plates 1 and 2 which are formed with bearings 3 and 4 for a shaft 5 which is rotated by any suitable means. Clamped between the upper parts of the side plates 1 and 2 is a core 6 carrying a current 75 generating coil 7 of the usual construction. Attached to the core 6 are pole pieces 8 and 9 having curved faces 10 and 11 respectively. Mounted on the shaft 5 is a permanent magnet 12. This magnet is secured to the shaft 80 by a suitable key 13. The magnet 12 is provided with four poles 14, 15, 16 and 17, the outer faces of which are curved as at 18 about the axis of the shaft as a center. Alternate poles of the magnet are N and S 85 poles. The centers of adjacent poles are 90 degrees apart and the pole pieces 10 and 11 are similarly disposed so that they receive flux from adjacent poles of the magnet.

Freely mounted on shaft 5 are two non-magnetic plates 19 and 20. Between these plates and outside of the magnet there are sections 21, 22 and 23 of magnetic material and also sections 24, 25 and 26 of non-magnetic material. Suitable screws 27 pass 95 through these side plates 19 and 20 into these sections and secure the same together, thus forming a sleeve, which is freely shiftable about the shaft 5 as a center. The section 26 is provided with a handle 28 which 100 may be connected to the timing mechanism. The sections 21 and 22 of magnetic material are curved to conform to the faces of the pole pieces and also to the outer faces of the poles of the magnet and are disposed between these faces as clearly shown in Fig. 1 105 of the drawing. These sections 21 and 22 form auxiliary or shiftable pole pieces

which receive the flux from the poles of the magnet as the flux passes to the fixed pole pieces 10 and 11 and the core of the current generating coil. This sleeve with the shiftable pole pieces is shifted in the well known way as to position the pole pieces for maximum spark.

The section 23 is curved to conform to the outer faces of the poles of the magnet and 10 is of sufficient extent so as to short circuit the poles of the magnet which are remote from the pole pieces. Said magnetic section 23 is separated by the non-magnetic sections 24 and 26 from the pole pieces 21 and 22 so 15 that the presence of this magnetic section 23 does not effect the magnetism in said pole pieces. This magnetic section for short circuiting certain of the poles of the magnet is shown, described and claimed broadly in my 20 co-pending application Serial No. 113,117, filed August 4th, 1916.

It is obvious that minor changes in the details of construction may be made without departing from the spirit of the invention 25 as set forth in the appended claims.

Having thus described my invention, what I claim as new and desire to secure by Letters Patent, is:—

1. An ignition magneto comprising a stationary current generating coil, a core therefor, fixed pole pieces for said core, a rotating permanent magnet having a plurality of like poles, said pole pieces being so disposed relative to the magnet as to receive flux from 30 adjacent poles of said magnet and shiftable pole pieces between the fixed poles and the poles of the magnet furnishing flux thereto, and a magnetic section so disposed relative to the rotating magnet as to short circuit the 35 other poles of said magnet.

2. An ignition magneto comprising a stationary current generating coil, a core therefor, fixed pole pieces for said core, a rotating permanent magnet having a plurality of like poles, said pole pieces being so disposed relative to the magnet as to receive flux from 45 adjacent poles of said magnet and shiftable pole pieces between the fixed poles and the poles of the magnet furnishing flux thereto, a magnetic section so disposed relative to the rotating magnet as to short circuit the other poles of said magnet, said magnetic section being shiftable with the 50 pole pieces.

3. An ignition magneto comprising a stationary current generating coil, a core therefor, fixed pole pieces for said core, a four pole permanent magnet having alternate N and S poles, said pole pieces being so disposed as to receive flux from the adjacent 55 poles of the magnet and shiftable pole pieces disposed between the fixed poles and the

poles of the magnet furnishing flux thereto, and a magnetic section so disposed relative to the magnet as to short circuit the poles 65 which are remote from said shiftable pole pieces.

4. An ignition magneto comprising a stationary current generating coil, a core therefor, fixed pole pieces for said core, a four 70 pole permanent magnet having alternate N and S poles, said pole pieces being so disposed as to receive flux from the adjacent poles of the magnet and shiftable pole pieces disposed between the fixed poles and the 75 poles of the magnet furnishing flux thereto, and a magnetic section so disposed relative to the magnet as to short circuit the poles which are remote from said shiftable pole pieces, said magnetic section being connected 80 to and movable with said shiftable pole pieces.

5. An ignition magneto comprising a stationary current generating coil, a core therefor, fixed pole pieces for said core, a rotating permanent magnet having a plurality of like poles, said pole pieces being so disposed as to receive flux from adjacent poles of the magnet, a shaft carrying said magnet, non-magnetic side plates freely journaled on said 90 shaft, shiftable pole pieces disposed between the fixed pole pieces and the poles of the magnet, means for connecting said shiftable pole pieces to said side plates, a magnetic section connected with said side plates and 95 so disposed as to short circuit the poles of the magnet remote from said shiftable pole pieces.

6. An ignition magneto comprising a stationary current generating coil, a core therefor, fixed pole pieces for said core, a rotating permanent magnet having a plurality of like poles, said pole pieces being so disposed as to receive flux from adjacent poles of the magnet, a shaft carrying said magnet, non-magnetic side plates freely journaled on said 100 shaft, shiftable pole pieces disposed between the fixed pole pieces and the poles of the magnet, means for connecting said shiftable pole pieces to said side plates, a magnetic section connected with said side plates and 105 so disposed as to short circuit the poles of the magnet remote from said shiftable pole pieces, and non-magnetic sections carried by the side plates and separating said last 110 named magnetic section from the shiftable pole pieces.

In testimony whereof I hereunto affix my signature in the presence of two witnesses.

WILLIAM WARREN DEAN.
